STEPHEN W. LONG, OF LOUISVILLE, KENTUCKY

Letters Patent No. 70,585, dated November 5, 1867.

IMPROVED BRICK MACHINE.

The Schedule referred to in these Letters Patent and making part of the same.

TO ALL WHOM IT MAY CONCERN:

Be it known that I, STEPHEN W. LONG, of Louisville, Jefferson county, Kentucky, have invented a new and useful Brick Machine; and I hereby declare the following to be a full, clear, and exact description thereof, reference being had to the accompanying drawings, making part of this specification.

My invention relates to an arrangement of parts, whereby at each stroke of the machine a certain and uniform quantum of clay is measured off and subjected to the successive action of two compressing-plungers operating in connection with a suitable sliding mould, from which the clay is ejected in the form of bricks after having been thoroughly and uniformly compressed and kneaded.

Figure 1 is a sectional elevation of a brick machine embodying my invention.

Figure 2 is a similar view, representing the operating parts in a position the reverse of that in which they are shown in fig. 1.

Figure 3 is a detailed perspective view of the brick-moulds.

A represents a strong frame in which the several operating devices are mounted. B is the driving-shaft, which through suitable gearing communicates a rotary motion to the spiral mixer and ejector C, which is journalled in the "pug-mill" or mud-box D. E is a lever, having pivoted support upon the upright F, and vibrated in a vertical plane by motion derived from the driving-shaft B through the medium of the cam B', yoke B'', and connecting-rod G. By means of connecting-rods H H' the lever E is made to impart a vertical reciprocating motion to a plunger, I; and also to a box or frame, J, in which any desired number of moulds J' J'' are formed. K K' are plungers, reciprocating horizontally, one above the other, and moving alternately in opposite directions. The plungers K K' receive motion from the driving-shaft B through the medium of the eccentric M, connecting-rods L L' L'', and vibrating lever N, the latter being mounted upon the rock-shaft N'. The chambers in which the several plungers and mould-box traverse, and which guide the same in their operating positions, are formed in the frame or casting O.

In operation, the rotation of the spiral blade of C ejects the clay from box D through the throat D', whence it is forced into chamber o immediately beneath plunger I. The latter descends and serves to cut off or separate a definite quantity of clay in chamber o from that within the mud-box. The mud thus cut off is forced downward through chamber o into the chamber o', the plunger K having been previously retracted. While under the action of plunger K, the clay is enclosed on three sides by the walls of the chamber o, and is backed up by the plunger K, so that before the clay is finally compressed in the moulds, it undergoes a certain amount of effective compression, and is caused to assume the block-form represented at P; fig. 2. At the lower extremity of its stroke the plunger I has an interval of rest, during which the plunger K is moved forward sufficiently to close communication between the chambers o and o' upon which the accelerating action of the cam B' elevates the plunger I and mould-box J, the latter being brought to a position in line with the chamber o' just in time to receive the clay P, which is forcibly driven or pressed into the moulds J' J'' by the continued forward motion of the plunger K'. The moulds having been thus charged with clay, are depressed to a position in line with chamber o'', when the forward motion of plunger K' serves to eject the pressed bricks from the moulds J, as represented in fig. 2. The bricks are received upon an endless apron, a, which conveys them to a place of deposit or delivery, said apron being driven by any suitable connection with the main driving-shaft. As soon as the mould-box J commences to descend, the plunger K is retracted to admit into the chamber o' another quantum of clay from mud-box D, which clay is cut off and compressed by plunger I, and then forced into the moulds J' and discharged, as already explained. The edges of the moulds J' J'' at their receiving sides, are chamfered, as shown at j, to insure the ready entrance of the plungers. The compressive action of the plungers I and K in opposite directions serves to give the clay a uniform solidity or body, and enables me to manufacture pressed bricks of superior quality.

I claim herein as new, and of my invention—

1. The arrangement in a brick machine of two plungers I K, so as to form a measure, and to exert upon the clay compressive forces in directions perpendicular to each other, substantially as described.
2. The combination of the plungers I K K', sliding moulds J J' J'', chambers o o' o'', and pug-mill G D, all arranged and operating substantially as and for the purpose herein specified.

In testimony of which invention I hereunto set my hand.

STEPHEN W. LONG.
